UNITED STATES PATENT OFFICE.

VOTAW S. DURBIN, OF ST. LOUIS, MISSOURI, ASSIGNOR TO DURBIN AUTOMATIC TRAIN PIPE CONNECTOR COMPANY, OF ST. LOUIS, MISSOURI, A CORPORATION OF ARIZONA.

ELECTRICAL CONTACT DEVICE FOR TRAIN-COUPINGS.

1,190,526.

Specification of Letters Patent. Patented July 11, 1916.

Application filed July 5, 1912. Serial No. 707,761.

To all whom it may concern:

Be it known that I, VOTAW S. DURBIN, a citizen of the United States, residing in the city of St. Louis and State of Missouri, have 5 invented new and useful Improvements in Electrical Contact Devices for Train-Pipe Couplings, of which the following is a specification.

This invention relates to automatic train 10 pipe couplings of the type more particularly shown in my pending application, No. 693,650, filed April 27th, 1912, and No. 658,667, filed November 6th, 1911, the present case being, in effect, a division of 15 the latter application, and has for its object to provide a novel arrangement of contact devices for forming an electrical connection when the coupler-heads are interlocked.

In the train pipe coupling constructed according to my invention, each coupling head 20 is provided with a pyramidal projection and adjacent thereto with a rectangular opening, the projection of either coupling head being adapted to enter the opening in the 25 other when the two heads are brought together. This construction enables me to provide means for making electrical connection when the coupling heads are brought to interlocked relation in a way that will 30 insure a firm contact between the two members of the electrical connection, and which will also make the contact members self-cleansing. This latter object is attained by 35 providing for a sliding or wiping engagement of the two contact devices before they are brought to fixed positions, so that any particles of dust or foreign matter will be brushed off of the contacts, and the contact surfaces will always be kept clean and 40 smooth, insuring perfect connection.

In the accompanying drawing Figure 1 is a view in side elevation, partly in section, showing the train pipe coupling heads in interlocked relation, and with a portion of 45 one of the pyramidal projections partly broken away to show the location of two contact devices on one of the coupling heads; Fig. 2 is a plan view, also partly in section and partly broken away, showing two contact devices in engagement; and Fig. 3 is a 50 section on an enlarged scale taken on the line 3—3 of Fig. 1.

Referring now to the drawing, 1 indicates the forward end of a plunger, which is

mounted as shown in my application No. 55 693,650, above referred to, and the outer end of which is bifurcated and apertured. In the bifurcated portion 2 there is inserted an apertured projection 3 formed on the rear side of the coupler-head 4, and a pin 5 is 60 passed through the apertures in the bifurcated end of the plunger and in said projection whereby the coupler-head is pivotally mounted on said plunger. Each coupler-head has a pyramidal projection 6 at 65 one side, and adjacent thereto a rectangular opening 6^a for receiving the pyramidal projection on the mating coupling head. A central partition 7, which forms a continuation of the projection 6, forms the inner wall 70 of the said opening. To provide for forming an electrical connection the partition 7 is apertured at two points, and in these apertures there is inserted a gasket 8 of insulating material, each of the said apertures 75 being enlarged near its inner end to provide an annular recess 9, forming a shoulder 10, against which the correspondingly large part of the gasket seats.

The numeral 11 indicates a contact device, one of which is mounted in each of the gaskets, said contact device being in the form of a pin having a head 12, the outer face or surface of which is flat, except for a portion near the periphery of the head 80 where it is beveled, as indicated by 13, to enable the two contact devices of the respective coupling heads to more readily slide past and over each other into engagement. The opening in the gasket 8 is made 85 interdental to provide a shoulder 14 against which the head 12 may seat, and a similar shoulder 15 against which a coil spring 16 seats, the other end of said spring bearing 90 against the head 12. The outer end of the 95 contact pin 11 is reduced and screw-threaded, as indicated at 17, and on this reduced portion is mounted a washer 18 of insulating material, which is adapted to bear against the outer end of the gasket 8, and 100 which is held in such position by means of a nut 19, screwed on the part 17 of the pin. Mounted on the said reduced part, and adjacent to the nut 19, is a binding post 20 which is held in position by a nut 21. An 105 insulated electrical conductor 22 is connected to each binding post by a nut 23, said conductors passing through an opening 24 in

the plunger 1, and extending thence back through the casing supporting said plunger and underneath the car to the coupling head on the other end thereof.

5 I have described the electrical contact devices as applied to one coupling head, but it will be understood that the description applies indifferently to either coupling head, the said contact devices being mounted in 10 the same way and in a corresponding position in each coupling head. The springs 16 normally press the heads 12 outward and when the contact devices are brought into engagement they will be mutually pressed inward 15 against the resistance of these springs, and thereby held in firm contact. From the position of these said contact devices at opposing side faces of the coupler-heads it will be seen that when the coupling heads are 20 brought together the outer faces of the heads 12 of the contact devices move over each other under considerable pressure maintained by the springs 16, and the frictional engagement produced by this sliding contact 25 wipes the surfaces of the heads 12, and insures an intimate contact between them, resulting in perfect electrical connection.

I have not thought it necessary to describe in detail the remaining parts of the train 30 pipe coupling, but for the purpose of rendering the illustration clear I will state that the numerals 25, 26 and 27 illustrate, respectively, the air and steam pipes, the ends of which are secured to the coupler-heads, and 35 which are connected when the said heads are brought into interlocked relation. The construction of the coupling heads and connected parts is exactly the same as fully illustrated and described in my said application No. 693,650.

40 My invention enables me to provide for automatically effecting electrical connection throughout the length of a train whereby telephonic and telegraphic communication 45 may be established from one end thereof to the other, and of course with any particular car. This invention will be especially beneficial in use on long freight trains enabling

operators at the rear end of the trains to communicate with the engineer.

50

I claim:

In a coupling of the character described, a pair of mating coupler heads having juxtaposed longitudinal body portions whose meeting faces are adjacent to a median line 55 when in the coupled relation, each of said coupler heads having a lateral extension on one side of the body portion, a forward projection on said lateral extension, said projection being tapered toward its end and 60 square at its base with respect to the face of said lateral extension, and an oppositely-disposed lateral extension on the other side of the body portion, said last-mentioned lateral extension having an opening therein 65 which is a counterpart of the base portion of said forward projection, whereby the forward projection on the lateral extension of the one coupler head enters the opening in the meeting lateral extension of the other 70 coupler head, so that, in the coupled relation, said lateral extensions are brought together and the base portions of said projections co-operate with the walls of said openings to prevent lateral separation of the coupler 75 head, and co-operatively - opposed spring-pressed electrical contact members mounted in said body portions so as to work transversely thereof in the region of said lateral extensions, the axes of said contact members 80 substantially coinciding on a median line between the meeting faces of said lateral extensions when the coupler heads are in the coupled relation, and the ends of said contact members projecting normally beyond 85 the respective meeting longitudinal faces of said body portions and having their edges shaped so as to slide edgewise into engagement.

In testimony whereof, I have hereunto set 90 my hand in presence of two subscribing witnesses.

VOTAW S. DURBIN.

Witnesses:

BRUCE S. ELLIOTT,
STELLA HILL.
